(57) **CLAIM**

The ornamental design for a headboard for patient bed, as shown and described.

DESCRIPTION

FIG. 1 is a top front perspective view of a headboard for patient bed showing our new design;

FIG. 2 is a front elevation view of the headboard of FIG. 1; FIG. 3 is a rear elevation view of the headboard of FIG. 1; FIG. 4 is an end elevation view of a first end of the headboard of FIG. 1;

FIG. 5 is an end elevation view of a second end of the headboard of FIG. 1;

FIG. 6 is a top plan view of the headboard of FIG. 1; and, FIG. 7 is a bottom plan view of the headboard of FIG. 1. The broken lines shown in the figures depict environmental subject matter and portions that form no part of the claimed design.

1 Claim, 3 Drawing Sheets
